UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,960, dated November 8, 1892.

Application filed October 10, 1892. Serial No. 448,443. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of a heraldic or shield-like ornament with a fleur-de-lis ornament and two diagonal bars in the center of said shield ornament and a laurel-branch extending from the bottom of 15 said ornament upwardly on each side of said ornament, as represented in the accompanying drawing. These ornaments are arranged at regular distances apart, and between each of said ornaments is arranged a small fleur-de-lis ornament.

20 The design is printed in any desired color or colors or in bronze and colors upon tinted paper of any desired color.

What I claim is—25 The design for wall-paper herein shown and described.

Witness my hand this 7th day of October, 1892.

CHARLES BOOZE.
